UNITED STATES PATENT OFFICE.

THOMAS A. ANDERSON, OF LANCASTER, PENNSYLVANIA.

CIGAR-BUNCH CUTTER.

SPECIFICATION forming part of Letters Patent No. 739,278, dated September 22, 1903.

Application filed March 25, 1903. Serial No. 149,467. (No model.)

To all whom it may concern:

Be it known that I, THOMAS A. ANDERSON, a citizen of the United States, residing at Lancaster, in the county of Lancaster and State 5 of Pennsylvania, have invented certain new and useful Improvements in Cigar-Bunch Cutters; and I do hereby declare the following to be a full, clear, and exact description of the invention, such as will enable others skilled 10 in the art to which it appertains to make and use the same.

This invention relates to a cigar-bunch cutter; and the object of the invention is to provide a device by means of which a "long-filler" cigar-bunch may be cut in such a form 15 that a shapely cigar will result when said bunch is wrapped without interfering with the draft therethrough by reason of tightly-formed ends.

20 The invention consists of a peculiarly-constructed device into which the tobacco is fed and a cutting-knife operating in conjunction therewith.

25 The invention is more fully described in the following specification and clearly illustrated in the accompanying drawings, in which—

Figure 1 is a side elevation of my device. Fig. 2 is a plan view of the same. Fig. 3 is 30 a front view of the bunching-box. Fig. 4 is a rear view of the cutting-knife. Fig. 5 shows in two views the cigar-bunch that my device will cut. Fig. 6 shows the form of the completed cigar. Fig. 7 shows a leaf of tobacco taken from a cut bunch developed.

35 The numeral 1 designates the bunching-box, which is provided with a central longitudinal opening 2, extending through the same. This opening is of such a diameter 40 and intersects the sides 3 of the box for a distance approximately one-half of its length and at such an angle as to produce a reduced forward end having a mouth-shaped opening 2^a across the end of said box. To the top of 45 this box 1 is secured a vertical guide-rod 4. The box 1 is adapted for attachment at its rear to the feed device in any suitable manner, whereby the tobacco may enter the same for bunching and cutting.

50 The numeral 5 designates the cutter-head, the blades of which are arranged at an an-

gle to each other, so as to fit closely against the sides of the box near its reduced end. This cutter has two cutting edges 6, each of which shears off the tobacco projecting from the opening 2^a, formed at the reduced end of the box 1. The cutting-knife has a sleeve 7 formed on its top, which top is closed, and this sleeve travels up and down on the guide-rod 4. A link 8 is secured to the top of the sleeve 7 in any suitable manner, or, if desired, may be screwed to the end of said sleeve, and is provided with an arm 9 on either side, which depend below the bunching-box and are joined at their lower ends by 55 a suitable link 10, to which is connected an operating-rod 11, through which vertical motion is given to the cutting-knife. These arms 9 are preferably rigidly secured to the ends of the links 8; but, if desired, they 60 may be pivoted thereto. When the tobacco-bunches are entered into the box from the rear, the knife is caused to descend through the action of the operating links and rods 9, 10, and 11 and cut the bunches in the form 65 shown in Fig. 5 of the drawings, the portion 12 cut away from the rear of one bunch forming the front or tip of the next bunch. This form of bunch will permit a shapely cigar 14 to be rolled without endangering the 70 free draft. (See Fig. 6.)

In Fig. 7 I have shown what may be supposed to be a leaf of tobacco 13 that was contained in a bunch and cut on my device. After being developed as shown it reveals the 75 effect on each piece of tobacco in the bunch.

The device is operated automatically, the movement of the cutting-knife being vertical, while the bunching-box remains stationary.

By my present device the complete bunch is 80 cut at a single stroke of the knife and there is absolutely no waste, as the form of the bunch, when cut, as shown in Fig. 5 of the drawings, will illustrate.

Having thus fully described my invention, 85 what I claim, and desire to secure by Letters Patent, is—

A cigar-bunch cutter comprising a tapering box provided with a longitudinal opening intersecting the sides thereof, a guide-rod secured to the top of said box near its forward end, a collar moving on said rod, knives se- 90 100

cured to the collar at an angle to each other and in such a position as to slide against the sides of the box, links secured to the collar and passing below the box, a connection at 5 the free ends of the links and an operating-rod secured to the connection for reciprocating the blades.

In testimony whereof I affix my signature in presence of two witnesses.

THOMAS A. ANDERSON.
